The ornamental design for an electronic device, as shown and described.

DESCRIPTION

FIG. 1 is a front, right, bottom perspective view of an electronic device showing my new design.

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear, right, bottom perspective view thereof.
